UNITED STATES PATENT OFFICE.

OSCAR T. NELSON, OF CLEVELAND, OHIO, ASSIGNOR OF FIFTY PER CENT. TO C. A. BARNHOLTH, OF AKRON, OHIO.

INTERNAL-COMBUSTION ENGINE.

1,336,372.

Specification of Letters Patent.

Patented Apr. 6, 1920.

Application filed November 1, 1917. Serial No. 199,618.

To all whom it may concern:

Be it known that I, OSCAR T. NELSON, a citizen of the United States, residing at Cleveland, in the county of Cuyahoga and State of Ohio, have invented a certain new and useful Improvement in Internal-Combustion Engines, of which the following is a full, clear, and exact description.

This invention relates to an internal combustion engine, and embraces certain features of construction which enable it to be run in a given direction and in the reverse direction, as may be desired.

The invention further consists in certain details of construction and important results obtained thereby, as will appear more fully in the following specification.

Reference should be had to the accompanying drawings forming a part of this specification, in which Figure 1 is a top plan view showing two cylinders of the invention; Fig. 2 is a top plan view of a six-cylinder engine; Fig. 3 is a plan view of a rotary valve, and Fig. 4 is a vertical section through a cylinder of the engine and coöperating parts.

So far as the base of the engine, its crank shaft and coöperating parts is concerned, the engine is not generally different from usual types of engine.

The invention may be embodied in engines having various numbers of cylinders, but for the purpose of explanation and without forming any limitation to the invention, I have chosen to illustrate a six-cylinder engine.

Each cylinder comprises the cylindrical portion 1, having therein a piston 2, which is operated by a piston rod 3 connected to a crank shaft, not shown. The upper part of each cylinder is closed by a top member 4, which is bolted to the top of the cylinder, and coöperating with the top member 4 is what I term a cap 5, which is also provided for each cylinder. The top member 4 provides a chamber 6 within it, and communicating with the chamber is an opening adapted to receive a spark plug 7. The chamber at its upper portion has an intake port opening 8 which has a conical seat that coöperates with a valve head 9. The valve head is provided with a stem 10 and a downwardly extending skirt 11.

In the cylinder itself and at one side of the cylindrical opening in the cylinder is a

well 12. This well is closed at the upper portion by a closure member 13 which has a central extension 14 surrounded in part by a cup-shaped portion 15. The cup-shaped portion is adapted to receive the skirt 11 of the valve 9, the inner wall of the skirt coöperating with the central portion 14 of the member 13. The central portion 14 of the member 13 is provided with an opening through which extends the valve stem 10. It will be clear from the foregoing description that in the operation of the valve 9 it is guided by the engagement of the rod 10 and the skirt 11 of the valve with the coöperating portions of the member 13.

Upon the end of the rod 10 opposite to the valve 9 is a plunger 16. This plunger fits within the well or opening 12, engaging with the walls therein so as to have a close working fit.

The well 12 has communicating therewith a channel 17 which connects the lower part of the well 12 with the space above the cylinder in the head member 4 so that whatever may be the condition with regard to compression or exhausting in the chamber 6, the same condition in regard to the pressure will obtain within the well 12 at the lower portion thereof, and this condition of positive or negative pressure will exert its influence upon the under side of the plunger 16.

The lower portion of the member 13 has a downward extension 18 which engages with the upper portion of the plunger 16 so that the plunger cannot come up into close engagement with the under side of the member 13, but will be spaced somewhat from the member 13, to provide a space 19 between the top of the plunger 16 and the under portion of the member 13.

It will be understood from the foregoing construction that when the piston 12 is moving on its compression stroke, the pressure exerted beneath the valve 9 will cause it to move to its seat. This pressure will also be exerted upon the lower face of the plunger 16, and thus assist the valve 9 in moving to its seated position. When the piston 2 is moving upon its suction stroke, the suction produced by the movement of the cylinder acts upon the under side of the valve 9 as well as upon the under side of the plunger 16, and thereby causes the movement of the valve 9 to its unseated or open position.

There is in connection with each cylinder

employed in the engine such a valve 9 as described which is mounted and operable with respect to the piston and cylinder in the same manner as that which has just been described.

The space 19 which lies above the plunger 16 is by means of a suitable tube 20 connected with a similar space associated with another cylinder. That is to say, the space 19 associated with the first cylinder may be connected with a similar space which is associated with the fourth cylinder. The space 19 associated with the second cylinder may be connected with a similar space associated with a fifth cylinder, and in like manner the space portion of the third cylinder connected with a similar space upon the sixth cylinder. The particular cylinders connected which have been thus explained is merely stated by way of example, and is not to be understood as limiting in any way connecting other cylinders than those mentioned. The idea involved in thus connecting the similar spaces 19 is to connect similar spaces which are associated with pistons that are performing similar functions at different times, that is to say, the cylinders thus connected would be so chosen that in one cylinder the piston was moving on its compression stroke, while in the other cylinder the piston was moving upon its suction stroke.

Considering this feature it will be seen that if the cylinder with which the particular space 19 shown in Fig. 3 was connected by means of the tube 20, was upon its compression stroke, the piston 2 shown in Fig. 3 would be upon its suction stroke. As before explained, the movement of the piston 2 upon its suction stroke would tend to unseat the valve 9, but in addition to this, there would be supplied through the pipe 20 a pressure which would be effective above the plunger 16 to assist in causing it to descend. On the other hand, when the piston 2 is upon its compression stroke and the plunger 16 would be forced upward, there would in turn be a pressure created in the chamber or space 19 which would be communicated through the pipe 20 to the similar space 19 associated with the other cylinder with which the pipe 20 is connected. This would then assist in the operation of the valve similar to the valve 9 in causing it to be unseated.

In a suitable recessed portion provided in the upper part of the head 4 and the lower portion of the cap 5 there is a rotatable valve 21. This valve is at the central portion mounted upon a short shaft 22 which finds bearing at opposite ends in the cap 5 and the head 4. At the peripheral portion of the valve, there is an overlapping portion 5* of the cap 5 against which the valve 21 engages as it rotates.

Preferably the valve at its outer end is provided with an inwardly extending skirt or flange 23 which engages with a suitable annular wall formed in the upper portion of the head 4.

70

In the head 4 there is formed an annular wall 24 which is connected by means of a suitable pipe 25 with an outside source of oil under pressure. Oil therefore occupies the annular groove 24 and is under pressure. In the flange 23 of the valve there is an annular groove 26 which co-operates with one portion of the groove 24 so that oil is maintained in the groove 26 of the valve.

75

In the head 4 there is an annular packing ring 27 which packing ring is also in communication with the oil channel 24. Therefore, the oil being under pressure, acts not only as a lubricant for the ring, but as a packing as well. The pressure which is exerted by the oil in the channel 24 holds the valve, that is to say, the periphery thereof, into close contact at the top thereof with the extension 5* upon the cap 5.

80

The foregoing construction not only acts to lubricate the valve, but also forms a packing which prevents the escape of gases around the edge of the valve.

85

The head 4 is provided with three valve openings, an inlet valve opening 28, and an inlet valve opening 29, and an exhaust valve opening which is not shown in Fig. 4, but which is shown in dotted lines at 30 in Fig. 3. The relative position of the ports 28, 29, 30, is also shown in Fig. 3. The port openings 28 and 29 are in communication by means of a channel 31 which is formed in the head 4.

95

The opening which is closed by the valve 9 is therefore in communication with both the ports 28 and 29, and gas entering through either of these ports is thus available to be supplied to the cylinder as may be required.

100

The valve 21 is provided with a single opening 32, this opening 32 being adapted to co-operate with the various ports which are formed in the head 4. In accordance with the direction of rotation of the crank shaft, the port 32 in the valve 21 will co-operate with the intake port 28 and the exhaust port 30, or with the intake port 29 and the exhaust port 30. When the valve 21 rotates in a clockwise direction the port 32 will co-operate with the intake port 28 and the exhaust port 30, and under these conditions the cycle of operation of the piston 2 will be such that during its intake period the port 32 will be co-operating with the port 28 and the port 29 will be closed by the unperforated portion of the valve 21. At such time under the condition mentioned as the port 32 would co-operate with the port 29 the cylinder 2 is either under its compression stroke or at the firing stage, so that the valve 9 is closed, and therefore the fact that the 115

120

125

130

port 32 coöperates with the port 29 produces no effect.

When the crank shaft rotates in a direction the reverse of that direction which it would rotate under the previously described conditions, the valve 21 will turn in a counter-clockwise direction and the port 32 will coöperate with the intake port 29 and the exhaust port 30. Under these conditions the cycle of operation of the piston 2 is such that the intake stroke of the piston occurs at a time when the port 32 registers with the port 29, and gas is admitted to the cylinder.

Under the conditions mentioned when the port 32 does coöperate with the port 28 it will be at a time when the piston is on its compression stroke, or during the firing period so that the valve 9 is held to its seat and the fact that the port 32 registers with the port 28 has no effect.

In the head 4 the chambers which coöperate with the ports 28 and 29 are separate and distinct. There is a chamber 33 which communicates with the port 8, and a chamber 34 which communicates with the port 29. These chambers are not connected directly with each other, but are only connected upon the opposite side of the valve 21 by the passageway 31. In other words, until the gas has passed through the port 32 in the valve 21 there is no communication so far as the ports 28 and 29 are concerned.

The valve 21 is operated by turning the shaft 22. The shaft at the end which extends upon the outside of the engine is provided with a disk 35 having a crank pin 36. Each of the cylinders is thus equipped and the several cylinders are connected to a common operating rod 37. This operating rod is suitably driven from the crank shaft in a manner which is not shown, but which is fully described and explained in my co-pending application, Serial No. 113227 filed

Jan. 19, 1917.

Each gas intake chamber in each of the caps 5 is quite similar and the intake chambers 34 upon successive cylinders are by means of pipes 38 connected with a manifold 39 which at a portion thereof communicates with a chambered member 40. This chambered member is provided with an upper chamber 41 and a lower chamber 42. The chamber 41 is connected with a source of fuel gas. The lower chamber 42 communicates through a port 43 with a chamber 44. From the chamber 44 there extends a pipe 45 which is connected with a source of air under pressure. Within the chamber 44 is a plunger 46 which is mounted upon a stem 47 and there is also upon the stem 47 a valve 48 which seats in a suitable port opening in the lower portion of the chamber 41. The relationship of the valve 48 and the plunger 46 is such that when the

valve 48 is closed the plunger 46 is in position to leave uncovered the port 43 so that air from the pipe 45 may pass to the chamber 42, thence to the manifold and to the various cylinders of the engine. 70

The rod 47 at its lower end extends into a suitable opening in the plunger 46 and seats against a spring 49 which is shown at the left hand portion of Fig. 3. This is for the purpose of providing a flexible connection between the valve stem 47 and the plunger 46, so that upon operation of the valve 48 and the plunger 46, the plunger may be held tightly to its seat. 75

Upon the side of the engine opposite to the chamber 40 there is a similar fuel gas chamber 50 and a similar air chamber 51 and a similar air supply pipe 52. The fuel supply chambers 50 and 40 may be connected to separate carburetors or the same carburetor, as may be desired. 80

The exhaust ports upon adjacent cylinders connect with a common chambered member such as indicated at 53 in Fig. 1, and these various chambered members 53 90 communicate with a common manifold for the exhaust gases.

In starting the engine, if it be desired to cause the crank shaft to rotate in one direction, we will assume that air under pressure is permitted to pass through the air pipe 45. Under these conditions the air will force the valve 46 from its seat, and the air will pass through the manifold to the several chambers 34 of the various cylinders. When the engine will have previously come to rest there will be one or more of the cylinders in which the port 24 of its valve 21 will be in position to admit air to pass through that port and through the port 29 into the upper portion of the cylinder. The air pressure thus exerted upon the top of the piston will cause the piston to descend and cause the crank shaft to rotate or turn over, thus giving an initial 100 turn to the crank shaft. 105

As soon as this takes place in the cylinder or cylinders under discussion, others of the cylinders will commence their suction stroke, and when the port 32 comes opposite the port 28 the suction produced will cause gas from the carburetor connected with the chamber 50 to be supplied through the manifold 39 and to the chamber 33 of the several cylinders. The suction thus produced will cause the valve 48 to assume the position shown at the left hand portion of Fig. 1 and inasmuch as there is no air pressure at the time within the pipe 52 there will be nothing to oppose the movement of 115 the valve to assume the position described. 120

It will be obvious as soon as a charge is introduced into the several cylinders which are thus under suction, it being assumed that the ignition apparatus is in proper working 125 130

order, explosions of compressed gas will take place and the engine be started.

On the other hand, if it be desired to cause the crank shaft to turn in the opposite direction, air under pressure will be admitted through the pipe 52 which will cause the same operations with respect to the valve 48^a as that which has been described with respect to the valve 48, and 10 under conditions last named the cylinders under their suction stroke will receive their fuel-gas by way of the chamber 34.

Having described my invention, what I claim is:

- 15 1. In an internal combustion engine, the combination with a cylinder having a piston therein and a cylinder head, of a rotatable valve within said head, said head being provided with two inlet openings and an exhaust opening, said valve being provided with an opening which in turning in one direction coöperates with one of the inlet openings and the exhaust, and when turning in the opposite direction coöperates with 20 the other of the inlet openings and the exhaust, means connecting said inlet openings, a single valvular means controlling the passage of gas from the inlet openings to the cylinder, said valvular means being moved to closed position when gas under pressure is within the cylinder, and means for operating the rotatable valve to coöperate with either of the inlet ports and the exhaust port.
- 25 2. In an internal combustion engine, the combination with a cylinder having a piston therein and a cylinder head, said cylinder head providing a space above the cylinder for the reception of fuel gas, a rotatable valve within the cylinder head, said head being provided with two inlet openings and an exhaust opening, said valve being provided with an opening which when turning in one direction coöperates with one of the 30 inlet openings and the exhaust, and when turning in the opposite direction coöperates with the other of the inlet openings and the exhaust, said cylinder head having chambered portions adjacent the inlet openings, and said head being provided with a channel-way which connects the chambered portions, said cylinder head being provided with an opening which controls the passage of fuel gas from the chambers adjacent the 35 inlet openings to the chamber in the head above the cylinder, valvular means coöperating with the said opening, said valve being moved to closed position when gas under pressure is within the cylinder, and means 40 for operating the rotatable valve to coöperate with either of the inlet ports and the exhaust port.
3. In an internal combustion engine, the combination with a cylinder having a piston therein and a cylinder head, said cylinder head being provided with a chamber which coöperates with the open end of the cylinder, said head being provided with two inlet ports and an exhaust port, there being chambers formed in the said head adjacent the said inlet ports, the chamber having a passageway by which the chambers adjacent the inlet ports are in communication, an opening in the cylinder head by which fuel gas may pass from the chambers adjacent the inlet openings to the chamber adjacent the open end of the cylinder, valvular means controlling the passage of gas through the said openings, said valvular means being moved to closed position when gas under pressure is within the cylinder, separate fuel receiving chambers formed in the said cylinder head, each of said fuel receiving chambers communicating with one of the inlet ports, a rotatable valve mounted within the cylinder head, said rotatable valve being provided with an opening which coöperates when turning in one direction with one of the inlet ports and the exhaust openings, and when turning in the opposite direction coöperates with the other of the inlet openings and the exhaust, and means for operating the rotatable valve to coöperate with either of the inlet ports and the exhaust port.
4. In an internal combustion engine, the combination with a cylinder having a piston therein and a cylinder head, said cylinder head having a partition therein which forms a chamber in communication with the open end of the cylinder, said partition being provided with an opening, valvular means coöperating with the said opening, which valvular means is moved to closed position when gas under pressure is within the cylinder, said cylinder head being provided with two gas receiving chambers, there being inlet ports formed in the head which communicate with the gas receiving chambers, each of said inlet ports having a chamber in communication therewith, the said chambers adjacent the inlet ports being in communication, a rotatable valve within the cylinder head and controlling the passage of gas from the gas receiving chambers through the inlet ports, said rotatable valve being provided with an opening which coöperates with one of the inlet openings and the exhaust opening when the valve is turned in one direction, and coöperates with the other of the inlet openings and the exhaust when the valve is turned in the opposite direction, and means for operating the rotatable valve to coöperate with either of the inlet ports and the exhaust port.
5. In an internal combustion engine, the combination with a cylinder having a piston therein and a cylinder head, said cylinder head being provided with a partition which forms a chamber adjacent the open end of

der head being provided with a chamber which coöperates with the open end of the cylinder, said head being provided with two inlet ports and an exhaust port, there being chambers formed in the said head adjacent the said inlet ports, the chamber having a passageway by which the chambers adjacent the inlet ports are in communication, an opening in the cylinder head by which fuel gas may pass from the chambers adjacent the inlet openings to the chamber adjacent the open end of the cylinder, valvular means controlling the passage of gas through the said openings, said valvular means being moved to closed position when gas under pressure is within the cylinder, separate fuel receiving chambers formed in the said cylinder head, each of said fuel receiving chambers communicating with one of the inlet ports, a rotatable valve mounted within the cylinder head, said rotatable valve being provided with an opening which coöperates when turning in one direction with one of the inlet ports and the exhaust openings, and when turning in the opposite direction coöperates with the other of the inlet openings and the exhaust, and means for operating the rotatable valve to coöperate with either of the inlet ports and the exhaust port.

4. In an internal combustion engine, the combination with a cylinder having a piston therein and a cylinder head, said cylinder head having a partition therein which forms a chamber in communication with the open end of the cylinder, said partition being provided with an opening, valvular means coöperating with the said opening, which valvular means is moved to closed position when gas under pressure is within the cylinder, said cylinder head being provided with two gas receiving chambers, there being inlet ports formed in the head which communicate with the gas receiving chambers, each of said inlet ports having a chamber in communication therewith, the said chambers adjacent the inlet ports being in communication, a rotatable valve within the cylinder head and controlling the passage of gas from the gas receiving chambers through the inlet ports, said rotatable valve being provided with an opening which coöperates with one of the inlet openings and the exhaust opening when the valve is turned in one direction, and coöperates with the other of the inlet openings and the exhaust when the valve is turned in the opposite direction, and means for operating the rotatable valve to coöperate with either of the inlet ports and the exhaust port.

5. In an internal combustion engine, the combination with a cylinder having a piston therein and a cylinder head, said cylinder head being provided with a partition which forms a chamber adjacent the open end of

the cylinder, valvular means controlling said opening in the partition, said valvular means being moved to closed position when gas under pressure is within the cylinder head, inlet passageways formed in the cylinder head between the said valve and the said partition, the said inlet passageways being in communication with each other, the said cylinder head being provided with 5
10 gas receiving chambers, said valvular means being provided with an opening which is adapted to coöperate with one of the inlet openings when turning in one direction, and to coöperate with the other of said inlet 15 openings when turning in the opposite direction, the said rotatable valve controlling the passage of gas from the gas receiving chambers in the cylinder head to the inlet openings, separate manifold connection to 20 each of said inlet chambers, and means for operating the rotatable valve to coöperate with either of the inlet ports.

6. In an internal combustion engine, the combination with a cylinder having a piston 25 therein and a cylinder head, of a rotatable valve within the cylinder head, said head being provided with two inlet openings and an exhaust opening, said valve being provided with an opening which when the valve 30 turns in one direction coöperates with one of the inlet openings and the exhaust and when the valve turns in the opposite direction coöperates with the other of the inlet openings and the exhaust opening, said cylinder head being provided with separate gas receiving chambers, each of which coöperates with one of the inlet ports, and means for operating the first mentioned valve to coöperate with either of the inlet ports and 35 the exhaust port.

7. In an internal combustion engine, the combination with a cylinder having a piston therein and a cylinder head, of a rotatable valve within the cylinder head, said head being provided with two inlet openings and an exhaust opening, said valve being provided with an opening which when the valve turns in one direction coöperates with one of the inlet openings and the exhaust and 50 when the valve turns in the opposite direction coöperates with the other of the inlet openings and the exhaust opening, said cylinder head being provided with separate gas receiving chambers, each of which coöperates with one of the inlet openings, a separate manifold connected with each of said gas receiving chambers, and means for operating the said rotatable valve to coöperate with either of the inlet ports and the 55 exhaust port.

8. In an internal combustion engine, the combination with a cylinder having a piston therein and a cylinder head, of a rotatable valve within the cylinder head, said head being provided with two inlet openings and 60

an exhaust opening, said valve being provided with an opening which when the valve turns in one direction coöperates with one of the inlet openings of the exhaust and when the valve turns in the opposite direction coöperates with the other of the inlet openings and the exhaust opening, said cylinder head being provided with separate gas receiving chambers, a separate manifold coöperating with each of the said gas receiving chambers, an air conduit and a gas conduit connected with each of said manifolds, valvular means controlling the passage of air from the gas conduit and the air conduit to the manifold, said valve being operated by the pressure of the air or gas, the valve being moved to close the gas conduit when air is admitted through the air conduit, and being moved to close the air conduit when gas is admitted through the gas conduit.

9. In an internal combustion engine, the combination with a cylinder having a piston therein and a cylinder head, of a rotatable valve within the cylinder head, said head being provided with two inlet openings and an exhaust opening, said valve being provided with an opening which when the valve turns in one direction coöperates with one of the inlet openings of the exhaust and when the valve turns in the opposite direction coöperates with the other of the inlet openings and the exhaust opening, said cylinder head being provided with separate gas receiving chambers, each of which coöperates with an inlet port, a separate manifold coöperating with each gas receiving chamber, each of said manifolds having an air conduit and a gas conduit connected therewith, a movable valve having a valvular portion which controls the passage of air from its conduit to the manifold, and also having a valvular portion which controls the passage of gas to the manifold, the said valve when in position to permit the flow of either the gas or air, preventing the flow of the other, and means for operating the first mentioned valve to coöperate with either of the inlet ports and the exhaust port.

10. In an internal combustion engine, the combination with a cylinder having a piston therein and a cylinder head, of a rotatable valve within the cylinder head, said head being provided with two inlet openings and an exhaust opening, said valve being provided with an opening which when the valve turns in one direction coöperates with one of the inlet openings and the exhaust and when the valve turns in the opposite direction coöperates with the other of the inlet openings and the exhaust opening, said cylinder head being provided with two separate gas receiving chambers, separate manifolds coöperating with each of said gas

- receiving chambers, an air conduit and a fuel gas conduit coöperating with each of the said manifolds, valvular means associated with each manifold, permitting the flow of either air or fuel gas and preventing the flow of the other, the relation being such that when air is admitted through one manifold thereby creating a pressure to start the movement of the piston, gas will be supplied to the engine through the other of said manifolds.
11. In an internal combustion engine the combination with a plurality of cylinders, each of said cylinders having a cylinder head, a rotatable valve within each cylinder head, each cylinder head being provided with two inlet and an exhaust openings, said valve being provided with an opening which when turning in one direction coöperates with one of the inlet openings and the exhaust opening, and when turning in the other direction coöperates with the other of the inlet openings and the exhaust opening, means for operating said rotatable valves, the several valves in the cylinders being set so as to effect a different timing in each of the said cylinders, each cylinder head being provided with two fuel gas receiving chambers, two manifolds, each manifold coöperating with one of the gas receiving chambers upon each cylinder, an air conducting conduit and a fuel gas conduit coöperating with each of the said manifolds, valvular means for controlling the passage of air and fuel gas whereby when either air or gas is supplied to the manifold the other is shut off, the relationship between the several parts being such that when air is supplied to one manifold for the purpose of effecting movement in such of the cylinders as are in condition to receive the air, fuel gas will be supplied to the cylinders through the other of said manifolds.
12. In an internal combustion engine, the combination of a plurality of cylinders each having a piston therein, and each provided with a cylinder head, a rotatable valve within each cylinder head said head being provided with an inlet valve and an exhaust valve, the rotatable valve being provided with an opening which when the valve turns coöperates with the aforesaid openings, a valve for controlling the passage of gas from the inlet opening to the cylinder, a plunger upon which said valve is mounted, a casing for the plunger the lower portion of said casing beneath the plunger being connected with the portion of the cylinder which is above the piston whereby the valve is operated in accordance with the pressure conditions in the upper part of the cylinder, the said casing providing an inclosed space above the plunger, the several spaces above the plungers for the different cylinders being interconnected in such a manner that when there is a period of compression in one of the cylinders the cylinder with which it is connected will be upon its exhaust stroke.
- In testimony whereof I hereunto affix my signature.

OSCAR T. NELSON.
